UNITED STATES PATENT OFFICE.

JAMES P. WILLIAMS, OF MILTON, PENNSYLVANIA.

BUILDING BLOCK.

1,405,644.

Specification of Letters Patent. Patented Feb. 7, 1922.

Application filed February 4, 1918. Serial No. 215,347.

To all whom it may concern:

Be it known that I, JAMES P. WILLIAMS, a citizen of the United States of America, residing at Milton, in the county of Northumberland and State of Pennsylvania, have invented certain new and useful Improvements in Building Blocks, of which the following is a specification, reference being had therein to the accompanying drawing.

10 This invention comprises a building block or tile. It is contemplated to provide a device of this character wherein there will be arranged a plurality of insulated air spaces separated by webs so as to provide 15 a plurality of chambers, the arrangement being such that the structure will withstand a maximum amount of stress commensurate with a light weight.

It is further contemplated to provide a 20 structure which will lend itself especially for use in the construction of walls and the like whereby a maximum amount of surface may be covered with a minimum amount of mortar or the like; which will provide a 25 ready means of handling; which will prevent moisture being carried across the block or tile through the mortar due to capillary attraction; upon which the mortar can be spread readily by the operator, in such a manner 30 that it is not necessary for him to come in contact with the mortar; and which will lend itself readily for use with a header or cross tile, turning corners, and the like.

Other objects and advantages will in part 35 be apparent and in part be brought out more fully in the description which follows:

A drawing illustrating an embodiment of the invention is hereto appended, the following views being shown:—

40 Figure 1, is a view in perspective;

Figure 2, is a view in vertical section illustrating an aggroupment of the blocks to form a wall.

Figure 3 is an end elevation of a modified 45 type of block.

Referring specifically to the drawings, the block or tile which constitutes this invention comprises a body portion or base member 1 of any suitable shape but preferably elongated to form a square or rectangle, and having on its side extremities upstanding members 2. In spaced relation to these upstanding members 2, there are centrally disposed web members 3 connected thereto by cross members 4 all elongated and corresponding in length preferably to the base

member 1 to constitute two spaced apart hollow chambers 5.

Intermediate the upper and lower edges of the web members 3 there is a cross web 6 connecting these members, this web being in spaced relation to the base plate or body portion 1 of the tile, and preferably of the same length as the tile to constitute therewith another chamber or air space 7.

Upon the cross web 6 extending upwardly therefrom and in spaced relation to the inner edges of the web members 3 there is a central web 8. This web is also of the same length preferably as the tile and its upper edge is in approximate alinement with the upper surfaces of the cross members 4 so that when the blocks are aggregated as shown in Fig. 2, and cement, mortar, or other binding instrumentality 9 has been placed between the blocks, in the manner shown therein, there will be a space approximately the thickness of the binder used, between the top of the central web member 8, and the bottom of the next succeeding tile. The upper portion of this web 8 is preferably flared as at 9' to provide a good grip for the operator in handling, and the mortar or the like 9 is preferably spread on the upper surface of the cross members 4 only, so that when holding the brick by the flared portion of the web 8 it is not necessary for the operator to come in contact with the mortar, and when the tiles have been arranged in the manner shown in Fig. 2, the central web 8 will form with the web members 3 two centrally disposed chambers 10 and 11, whereby any moisture which may be carried between the bricks through the cement or mortar 9 will be deposited in one of these chambers, and there is no opportunity for the mortar on either side of the brick to contact and thus form a conductor for moisture to carry it across the wall.

The arrangement of the webs in the manner set forth, provides a building block having on either side thereof an elongated chamber or air space entirely enclosed on four sides by walls or webs which constitute an elongated chamber open at its ends, 105 and the cross web 6 connecting these chambers constitutes a brace, which together with the adjacent portion of the base or body 1 of the tile forms another elongated chamber or air space 7. This arrangement forms an 110 effectual brace for the structure and minimizes the danger of the tile breaking cen-

trally which frequently happens when no such provision is made.

The arrangement of the centrally disposed upright web 8 upon the cross web 6, 5 in the manner shown provides a means of buttering or spreading the mortar, whereby it is not necessary for the operator to have his hands come in contact with it, and the flared portion of the web permits him to 10 secure a good grip on the tile.

It will be noted that there is no interlocking feature in this tile as so far described and that the arrangement of the two chambers or air spaces 5 upon the base 15 1 constitutes practically two separate bricks of the type now so generally in use, and so connected and braced that it is merely necessary to spread the mortar or binding element 9 upon the ends and upper surfaces 20 of these members; and the central web 8 being at its upper edge in approximately the same plane and not protruding beyond the surface of the cross members 4, a cross brick or binder can be effectively 25 used without having to be of special shape or formation. The same facility is insured in turning a corner or in corner construction, owing to the absence of protruding parts and the approximately rectangular 30 shape of the tile.

Where it is desired to provide for an interlocking or offset arrangement, the base member 1 may be distorted in the manner indicated in Fig. 3, wherein the base member 35 is bent centrally to constitute a wave like arrangement wherein there is provided two depending portions or projections 12 and 13 which extend below the plane of the lower surface of the base portion, and an upwardly projecting portion 14 extending 40 into the air space 7. This arrangement provides an offset in the lower face of the tile which is a substitute for the projections heretofore so common in use, and might 45 be considered in the nature of an offset.

It is likewise contemplated in the manufacture of this block or tile, to provide instead of the angular corner shown in Figs. 1 and 2, on the interior of the air chambers, 50 rounded corners as indicated at 15 in Fig. 3. This arrangement provides a strengthening or additional reenforcement for the web members, and facilitates the manufacture of the block and its removal from the dies.

From the foregoing it will be apparent 55 that the building block or tile which comprises the present invention constitutes a simple and effectual means of meeting the advantageous and avoiding the disadvantageous features above set forth, and while it has been described and illustrated in the embodiment herein shown, it will be understood that I do not wish to limit myself to the precise form of this disclosure, as 60 many changes in the construction and gen-

eral arrangement of the parts may be made without departing from the spirit of the invention as set forth in the claims.

What I claim is:—

1. A building brick comprising a base, 70 the portions of which are in approximately the same plane, a plurality of spaced-apart chambers disposed on said base; a cross-web arranged in spaced relation to the base and connecting said chambers, and constituting, with said chambers and base, an elongated air-chamber; and an upright web upstanding from said cross-web in spaced relation to said chambers, the outer surface of said upright web being in approximately the same plane as one of the outer edges of said chambers. 75

2. A building brick comprising a base; a plurality of upright members arranged in spaced relation upon said base; cross-members connecting certain of said upright members and constituting therewith and with said base a plurality of hollow spaced-apart chambers; a cross-web connecting two of the upright members between certain of said chambers, said cross-web being in spaced relation to the base, and forming therewith and with certain of the upright members, a hollow chamber disposed between the other chambers; the portion of the base juxtaposed to said cross-web being in approximately the same plane as the corresponding portion of the base disposed opposite the other cross-members; and an upright web disposed on said cross-web in spaced relation to certain of the upright members, the outer surface of said upright web being in approximately the same plane as one of the outer surfaces of said chambers. 95

3. A building brick comprising a base; upright and cross members joined together and to said base to constitute a plurality of spaced-apart chambers disposed upon said base; a cross-web connecting certain of said 100 upright members and arranged in spaced relation to a portion of the base, to constitute, with the upright members and said portion of the base, an elongated chamber disposed between the other chambers; the portion of the base disposed opposite the cross-web being in approximately the same plane as the corresponding portions of the bases of the other chambers; and an upright web disposed upon the cross-web and in spaced relation to certain of the upright members and dividing the space between the chambers, the outer surface of said upright web extending 115 to approximately the plane of one of the outer surfaces of said chambers. 105

4. A building brick comprising a plurality of spaced-apart load-sustaining members having their upper and lower surfaces, respectively, lying in common planes, the lower surfaces constituting base-portions 120

125

- thereof, a horizontal transverse web connecting the base-portions and forming with said base-portions a base for the brick, an upper horizontal transverse web connecting the 5 load-sustaining members above the base web and arranged substantially below a plane passing horizontally through the centers of said members, and a central longitudinal web integral with and upstanding from said 10 upper horizontal web and disposed between and spaced from the side members and adapted for the purposes of a hand-hold, all parts of the brick being included between the planes of the upper and lower surfaces of 15 the load-sustaining members.
5. A building brick comprising a plurality of hollow spaced-apart load-sustaining members having their upper and lower surfaces, respectively, lying in common planes, the 20 lower surfaces constituting base-portions thereof, a horizontal transverse web connecting the base-portions and forming with said base-portions a base for the brick, an upper horizontal transverse web connecting the 25 load-sustaining members above the base-web and arranged substantially below a plane passing horizontally through the centers of said members, and a central longitudinal web integral with and upstanding from said 30 upper horizontal web and disposed between and spaced from the side members and adapted for the purposes of a hand-hold, all parts of the brick being included between the planes of the upper and lower surfaces 35 of the load-sustaining members.
6. A building brick comprising a plurality of spaced-apart load-sustaining members
- having their upper and lower surfaces, respectively, lying in common planes, the lower surfaces constituting base-portions, a horizontal transverse web connecting the base-portions and forming therewith a base for the brick, an upper horizontal transverse web disposed in parallelism with the base-web and connecting the load-sustaining members at a point substantially below a plane 40 passing horizontally through the centers of said members and forming with the base-web and the members a central air cell, and a central longitudinal web integral with the 45 upper transverse web between the side members and spaced therefrom and adapted for the purpose of a hand-hold, all parts of the brick being included between the planes of the upper and lower surfaces of the load-sus- 50 taining members.
7. A building brick comprising a plurality of spaced-apart load-sustaining members, the lower surfaces of which constitute base-portions, a horizontal transverse web connecting the base-portions and forming therewith a base for the brick, a member-connecting web disposed in parallelism with the base-web, and a longitudinal web disposed 55 centrally of and spaced from the side members and adapted for the purpose of a hand-hold.

In testimony whereof I affix my signature
in presence of two witnesses.
